(57) CLAIM

The ornamental design for a gold bar-shaped container for alcoholic and non-alcoholic beverages, as shown and described.

DESCRIPTION

FIG. 1 is a perspective view of the new vodka bottle in accordance with my design;

FIG. 2 a front side view of the new vodka bottle in accordance with my design;

FIG. 3 is a rear side view of the new vodka bottle in accordance with my design;

FIG. 4 is a left side view of the new vodka bottle in accordance with my design, while a right side view thereof is identical with the left side view;

FIG. 5 is a top plan view of the new vodka bottle in accordance with my design;

FIG. 6 is a bottom plan view of the new vodka bottle in accordance with my design; and,

FIG. 7 is a perspective view of the new vodka bottle with an open lid in accordance with my design.

The broken line showing of the indicia is for illustrative purposes only, and forms no part of the claimed design.
